US00D719254S

(12) **United States Design Patent**
Moore et al.

(10) **Patent No.:** US D719,254 S
(45) **Date of Patent:** ** Dec. 9, 2014

(54) **ELBOW CONNECTOR FOR RESPIRATORY MASK**

(71) Applicant: **ResMed Limited**, Bella Vista (AU)

(72) Inventors: **Rachael Elizabeth Moore**, North Bondi (AU); **Philip Rodney Kwok**, Chatswood (AU); **Andrew Martin Price**, Baulkham Hills (AU); **Saad Nasr**, Oatley (AU); **Anthony Michael Ging**, Heathcote Valley (AU)

(73) Assignee: **ResMed Limited**, Bella Vista (AU)

(**) Term: **14 Years**

(21) Appl. No.: **29/467,135**

(22) Filed: **Sep. 16, 2013**

Related U.S. Application Data

(60) Continuation of application No. 29/436,717, filed on Nov. 8, 2012, now Pat. No. Des. 690,003, which is a division of application No. 29/419,831, filed on May 2, 2012, now Pat. No. Des. 673,263, which is a continuation of application No. 29/311,142, filed on Dec. 31, 2008, now Pat. No. Des. 660,412, which is a division of application No. 29/295,746, filed on Oct. 5, 2007, now Pat. No. Des. 588,690, which is a continuation of application No. 29/323,874, filed on Jun. 24, 2005, now Pat. No. Des. 552,731, which is a continuation of application No. 29/213,364, filed on Sep. 16, 2004, now Pat. No. Des. 540,941, which is a division of application No. 29/189,972, filed on Sep. 15, 2003, now Pat. No. Des. 507,348, which is a division of application No. 29/166,190, filed on Aug. 9, 2002, now Pat. No. Des. 485,905.

(57) **CLAIM**

The ornamental design of an elbow connector for respiratory mask, as shown and described.

DESCRIPTION

FIG. 1 is a perspective illustration of an elbow connector for respiratory mask according to our new ornamental design;

FIG. 2 is a top view thereof;

FIG. 3 is a bottom view thereof;

FIG. 4 is a right side view thereof; and,

FIG. 5 is a front view thereof.

The broken lines in the drawing figures are included to show unclaimed portions only and form no part of the claimed design.

1 Claim, 3 Drawing Sheets
